(74) **Attorney, Agent, or Firm:** William H. Honaker; Dickinson Wright PLLC(57) **CLAIM**

The ornamental design for a visor for helmet respirator, as shown and described herein.

DESCRIPTION

FIG. 1 is a perspective view of the visor for helmet respirator of the present invention.

FIG. 2 is a top view of the visor for helmet respirator of the present invention.

FIG. 3 is a front view of the visor for helmet respirator of the present invention.

FIG. 4 is a rear view of the visor for helmet respirator of the present invention.

FIG. 5 is a bottom view of the visor for helmet respirator of the present invention.

FIG. 6 is a right side view of the visor for helmet respirator of the present invention; and,

FIG. 7 is a left side view of the visor for helmet respirator of the present invention.
